US0D1104369S

(12) **United States Design Patent** (10) Patent No.: **US D1,104,369 S**
Abdi et al. (45) Date of Patent: ** Dec. 2, 2025

(54) **BOWL**

(71) Applicant: **Merrick Engineering, Inc.**, Corona, CA (US)

(72) Inventors: **Abraham Abdi**, Newport Coast, CA (US); **Terryl Lee Oster**, Lorena, TX (US); **Kasin Chan**, Chino, CA (US)

(73) Assignee: **Merrick Engineering, Inc.**, Corona, CA (US)

(**) Term: **15 Years**

(21) Appl. No.: **29/866,620**

(22) Filed: **Sep. 20, 2022**

(51) LOC (15) Cl. **30-03**

(52) U.S. Cl.

USPC **D30/130; D30/121**

(58) **Field of Classification Search**

USPC D30/121, 129, 130, 131, 133, 160

CPC A01K 5/0114; A01K 15/025

(57) **CLAIM**

The ornamental design for a bowl, as shown and described.

DESCRIPTION

FIG. 1 is a top, front, and left side perspective view of the design for a bowl.

FIG. 2 is a bottom, rear, and right side perspective view thereof.

FIG. 3 is a front elevation view thereof.

FIG. 4 is a rear elevation view thereof.

FIG. 5 is a right side elevation view thereof.

FIG. 6 is a left side elevation view thereof.

FIG. 7 is a top plan view thereof.

FIG. 8 is a bottom plan view thereof; and,

FIG. 9 is a cross-sectional perspective view taken along and in the direction of the line 9-9 in FIG. 1.

The broken lines illustrate portions of the bowl that form no part of the claimed design.

1 Claim, 7 Drawing Sheets
